UNITED STATES PATENT OFFICE.

WORDSWORTH M. ELLIOTT, OF CRETE, AND SHELDON E. COOK, OF LINCOLN, NEBRASKA.

INTERCHANGEABLE SIGN LETTERS.

Application filed March 18, 1922, Serial No. 544,818. Renewed November 28, 1922.

To all whom it may concern:

Be it known that we, WORDSWORTH M. ELLIOTT and SHELDON E. COOK, citizens of the United States, residing, respectively, at 5 Crete, in the county of Saline and State of Nebraska, and Lincoln, in the county of Lancaster and State of Nebraska, have invented certain new and useful Improvements in Interchangeable Sign Letters, of 10 which the following is a specification.

This invention has reference to improvements in sign letters designed for being interchangeably assembled when building up out-door and indoor signs and insignia, for 15 ornamental advertising and formative as well as other purposes, especially where such letters are to be more or less individual in character or subject to change or alteration.

20 Primarily our invention seeks to provide an improved formation of sign letters of the general character stated that can be economically made and which, when of metal, may be shaped up by stamping or punching.

Another object of our invention is to provide all metal letter plates or units, stamped or otherwise formed of blank members, so designed that the said letter plates can be 30 conveniently telescopically connected, self-supported, and including interlocking elements such as will render the joined letters or sign fool-proof.

Another object of our invention is to provide sign letters shaped for sidewise telescopically engaging one another and adapted for being readily adjusted, either fully telescoped, or adjusted to more or less space apart the individual letters in such manner as the character of the sign, insignia or formative representation of the letters may 40 make most desirable.

With other objects in view that will be hereinafter explained our invention consists 45 of an improved construction and arrangement of sign letters embodying the peculiar features and detailed arrangement of parts fully described in the following description, specifically set out in the appended claims, 50 and illustrated in the accompanying drawings, in which:

Figure 1 is a face view of a portion of a sign formed with our improved individual sign letters, the several letters being shown

at their innermost telescopically engaged 55 connection, a preferred construction being illustrated.

Figure 2 is a similar view which shows the several individual plates separated to widen the spaces between the letters that are 60 suitably delineated upon the said plates.

Figure 3 is a horizontal section taken along the line 3—3 on Figure 1.

Figure 4 is a similar sectional view taken on the line 4—4 of Figure 2.

Figure 5 is a plan view of the blank member from which the complete plate shown in Figures 1 to 4, is struck up.

Figure 6 is an enlarged detail horizontal section taken through one of the locking 70 mechanisms of our preferred form of letter unit structure, portions of a pair of such letters being shown telescopically connected and interlocked.

Figure 7 is a view similar to Figure 6, 75 a slightly modified form of letter unit being shown.

Figure 8 is a rear perspective of one of the letter plates and illustrates the preferred construction shown in Figures 1, 2, 3 and 6. 80

Figure 9 is a view similar to Figure 8, the modified form of letter shown in Figure 7 being illustrated.

Figure 10 is a face view of a further modified form of our sign, the letters being 85 shown connected to produce a portion of a sign.

Figure 11 is a horizontal section on the line 11—11 of Figure 9.

Figure 12 is a rear perspective view of 90 one of the letter plates shown in Figures 10 and 11, and hereinafter specifically referred to.

Figures 13 and 14 are rear perspective views of the sign end finishing piece shown 95 in Figure 10.

In the practical development of our invention and in the preferred form thereof, each letter character or ornamentation is embossed or applied upon an enlargement or 100 unit in the nature of a metal plate that is struck up or otherwise formed from a blank member, of the shape best shown in Figure 5 of the drawings, by reference to which it will be observed the said element or unit 105 comprises a main or body portion 1 upon the outer face of which is embossed, or applied in any suitable way, a letter 2.

At one side the body 1 has a flat extension 10 that is pressed back, in a plane parallel with the said body 1, the thickness of the metal, as is clearly shown in Figures 3 and 5 4, for the purpose of providing a smooth front finish of the several letter character elements or units when two or more of the said units are telescopically connected, as shown.

10 At the opposite (top and bottom) edges, the body 1 has turned back flanges 3—3, which flanges constitute keepers on one letter element or unit with which the extension 10 of an adjacent letter or unit telescopically engages, when assembling the different units in building up the sign, insignia or other formative or advertising matter, and to provide for a perfectly smooth finish at the top and bottom edges 15 of the sign, when the different units or elements are telescopically assembled, as in Figure 1, and the upper and lower edges of the extensions 10 are offset as at 11—11.

So far as described, in connection with 20 the drawings, it will be readily apparent that the several letter units may be quickly put together with their extensions 10 fully telescopied, as in Figure 1, or only partly so, when widened spaces between the letter 25 or other insignia are desired, as indicated in Figure 2.

To positively hold the letter units to their 30 assembled connection provision is made for holding them locked together and in the preferred form the back-turned flanges or keepers 3 are each provided with a series of perforations 30 and the corresponding top and bottom edges of the member 10, that telescopically engage the said keepers, 35 are provided with locking nibs 5 struck up from the said body portion 1, and which are sufficiently smooth to slip along the series of apertures 30 when fitting the latter units together to lock them spaced apart, or held 40 closely together, as the case may be, and also provide for pulling the said letter units apart, as desired, the nibs 5 riding along the keepers 3 when pulling the two letter units apart under some force.

45 Instead of providing a series of perforations 30 along the keepers the extensions 10 may be provided with a single locking aperture 6, at the top, and a like aperture at the bottom edge, and located next the adjacent offset side of the body portion 1, and the flanges or keepers in which each of the extensions 10 is telescopied and after the two units are slid together, the said flanges or keepers 3 are punched, just over the apertures 6, to provide locking nibs 60 for interlocking with the said apertures 6, as clearly shown in Figure 7.

50 In Figures 9, 10 and 11, is shown a further modification of our invention and in 55 this form, the letter units are provided with

means for positively locking them together and against being drawn apart by pulling, as is done in the preferred form shown in Figures 1 to 4.

55 In this modified form, the body portions each have keepers or flanges 3 at the top and bottom edges for receiving the extensions 10—10, as in the other form described, but in this latter form, the extensions 10 need not be as long as in the preferred form, for the reason that no provision is present in the said modified form to provide for different spacing of the letters, since in the said modified form the letter units are positively held assembled to the one position, 60 closely together, as shown in Figure 10.

65 In the said modified form, the body portion 1 at that side opposite the extension 10 has a longitudinal extension 7, and, at the vertical line of the offset, at the extension side, it has a slot 70, such body form providing for readily slipping the slot 70 over the tongue 7 of the adjacent unit when telescopically slipping the said extension 10 into connection with another letter unit, it 70 being apparent, by referring to Figure 10, that when the two letter units are slipped together, as stated, the tongue 7 of one unit can be quickly bent back and clamped over the cooperative extension 10 of the adjacent unit and the two units thereby held in a 75 positive interlocked condition.

80 In the said modified form, the letters or other face ornamentations are preferably shaped up of thin metal and they are provided with tongues 8 adapted for slipping through apertures 80 in the body 1 to clinch over the back of the said body 1, as shown, it being understood that in the different forms shown the letters or other face ornaments are embossed or fixedly applied to the other face of the body portion 1 in any manner well known in the art to which the invention applies.

85 It will be readily seen by reference to Figures 10, 13 and 14, that sign end finishing members may be provided, one being in the nature of a slip over plate 12 having turned over ends 13 for sliding over the flat projection 10 of the adjacent letter unit, and the one at the opposite end being similar in construction to one of the letter units, it being narrower in width, however, to correspond with the width of the slip over unit at the opposite end, and the said member 105 has a plain face 14, as shown.

90 The said finishing member 14 may also be provided with an interlocking tongue 7 (see dotted lines, Figure 13) to adapt the same to use between two letter units, as a 125 spacer unit, as may be desired.

95 From the foregoing description, taken in connection with the accompanying drawings, the complete construction and the manner in which our improved letter units 130

are assembled will be apparent to those familiar with the art to which our invention relates.

The advantages of the individual letters 5 are many, chiefly the way of cheapness of construction of words and sentences and the ease with which the lettering may be altered and varied, since by keeping a stock of letters constructed as shown and described, a 10 business man may build up his own advertising window, and for other uses such as outside door signs, indicating individual names and places of business, street signs, car signs, house numbers, etc., all of which 15 may be readily built up with our improved construction of letter units by anyone. By constructing the letter units as described and shown, a sign built up thereby is self-sustaining, needs no back support, the locking 20 features making tampering with the sign difficult, especially when the parts are positively held together, as stated and shown, and further it provides for making an interchangeable metal sign more cheaply 25 than a solid sign of the same material.

What we claim is:—

1. A formative indicator composed of a plurality of units each of like contour and each comprising a body portion on which 30 is received a letter or character, the said body portion having an extension at one side and having its upper and lower edges back-turned to form keeper flanges, the keeper flanges of one unit being adapted for 35 telescopically receiving the side extension of another unit, and means on the two units for holding them together.

2. A formative indicator composed of a plurality of units each of like contour and 40 each comprising a body portion on which is received a letter or character, the said body portion having an extension at one side and having its upper and lower edges back-turned to form keeper flanges, the keeper 45 flanges of one unit being adapted for telescopically receiving the side extension of another unit, the said extensions of the units being bent back in a plane in parallel with the front face of the body portion 50 whereby a uniform smooth finish of the letter or character surfaces of the said body portion of the units is provided for.

3. A formative indicator composed of a plurality of units each of like contour and 55 each comprising a body portion on which is received a letter or character, the said body portion having an extension at one side and having its upper and lower edges back-turned to form keeper flanges, the keeper 60 flanges of one unit being adapted for telescopically receiving the side extension of another unit, the said extensions of the units being bent back in a plane in parallel with the front face of the body portion whereby 65 a uniform smooth finish of the letter or

character surfaces of the said body portion of the units is provided for, the upper and lower edges of the side extensions being offset with respect to the body portion having the flanges or keepers to provide a uniform smooth upper and lower edge of the sign made up from a plurality of telescoped units.

4. A formative indicator composed of a plurality of units each of like contour and each comprising a body portion on which is received a letter or character, the said body portion having an extension at one side and having its upper and lower edges back-turned to form keeper flanges, the keeper flanges of one unit being adapted for telescopically receiving the side extension of another unit, the said extensions of the units being bent back in a plane in parallel with the front face of the body portion whereby a uniform smooth finish of the letter or character surfaces of the said body portion of the units is provided for, means on the keepers of one unit and the corresponding edges of the extension of an adjacent unit for interlocking the said extensions and the keepers to hold the adjacent ones of the units to their partial or wholly telescoped adjustment.

5. A formative indicator composed of a plurality of units of like contour each of the said units comprising a body portion on which is received a letter or character, the said body portion having an extension at one side and having its upper and lower edges turned back to constitute keeper flanges, the keeper flanges of one unit being adapted for telescopically receiving the side extensions of another unit and interlocking portions on the keepers and the extensions for holding the adjacent unit members to their adjusted position.

6. A formative indicator, composed of a plurality of units of like contour, each unit comprising a body portion on which is received a letter or character, each body portion having an extension at one side, the said extension being bent back in a plane parallel with the front face of the said body portion whereby a vertical offset of the full height of the unit is provided, the said body of the unit opposite its extension having a laterally projected punched tongue, the vertical offset at the other side of the body portion having a slot disposed in horizontal alignment with the tongue, whereby to provide for slipping the slot in one unit over the tongue of the adjacent edge of another unit when the two units are telescopically connected, the said tongue being adapted for being clinched back onto the extension of the unit having the slot for the purposes specified.

7. A formative indicator composed of a plurality of units each of like contour and each comprising a body portion on which is

received a letter or character, the said body portion having an extension at one side and having its upper and lower edges turned back to form keeper flanges, the keeper flanges of one unit being adapted for telescopically receiving the side extension of another unit, means on the two units for

holding them together and supplemental end units that telescopically engage the opposite end units and constitute sign end finishing portions.

W. M. ELLIOTT.
